UNITED STATES PATENT OFFICE

AUGUST F. SCHMIDT, OF ST. PETERSBURG, FLORIDA

CARTON-DISCHARGING DEVICE

Application filed March 23, 1928. Serial No. 264,013.

This invention relates to a novel carton discharging device having, among others, the novel features herein described and illustrated.

5 In the drawings of one embodiment of my invention illustrated and described herein,

Fig. 1 is a front elevation of the device on a carton;

Fig. 2, a vertical section on the line 2—2,
10 Fig. 1, partly broken away;

Fig. 3, a similar figure showing the device as it is applied to the carton and before it is locked thereon;

Fig. 4, a side elevation of the device;
15 Fig. 5, a plan thereof; and

Fig. 6, a perspective view of a carton punctured by the device, and before it is applied thereto.

Referring first to Figs. 1, 2, 5, my novel
20 carton discharger comprises a frame or plate 1, of metal or other proper material, of suitable size and outline with, Figs. 2, 3, an opening 2 therein. On its front face it has, in the present case, a projecting spout 3 with a self-closing lid 4 pivoted to the spout walls.

On the rear face of the spout, Figs. 2, 3, 4,
25 5, is a curved flange 5 with, Fig. 5, a sharp point 6 for conveniently puncturing the carton. Hinged or pivoted to the spout walls
30 in this case, is a frame locking and carton engaging member 7 slightly offset, Figs. 2, 3, within the frame, and then extended downwardly to form a loop 8 to engage the inner carton wall to hold the frame in firm engagement therewith. On the outer face of the frame, Figs. 1, 2, at any suitable point, is a fastening member as a catch 9 to receive the outer bar of the member 7, although a suitable member may be placed at any other convenient point. The flange 5 is provided with a slot 10, Figs. 2, 3, 4, which, when the spout is in position, Fig. 2, receives the edge of the carton at the opening therein and assists in holding the frame firmly in position.

40 In use the carton to which the spout is to be applied is preferably laid on its back or side to avoid spilling the contents, with the locking member 7 positioned outwardly, Fig. 3, the point 6 of the flange 5 is thrust through the wall of the carton, and forced inward

its full length. The flange is then withdrawn, the cut out portion 11, Fig. 6, of the carton is then either bent inwardly or outwardly, Fig. 2, against the carton wall or even torn off. The flange 5 is then again 55 inserted through the opening in the carton wall, and the member 7 swung upwardly, pressing the loop 8 against the inner carton wall, Fig. 2, and the offset sections of the member 7, engaging the edge 12 of the carton 60 wall, will force the frame and flange upwardly slightly so that the edge 13 of the carton wall will slide into the slot 10 and assist in holding the frame firmly to the carton. 65

Obviously it is not necessary, but convenient, that the flange 5 be of the carton puncturing type. If another form is desired for any reason, the necessary puncturing of the carton can be done by any convenient instrument and the flange then inserted and locked 70 in position. In either case the spout will function as well.

The present invention is particularly valuable as it not only provides a convenient delivery spout for any goods such as cereals, 75 sugar, rice, etc., but it provides its own carton puncturing means, of proper shape and size.

The spout is provided with a lid which keeps out of the carton flies, and insects of all 80 kinds, as well as dust. If desired, the spout can be omitted and only the lid used to close the opening in the frame.

The spout can, of course, be used on as many different cartons as is desired, and can 85 be manufactured at a low price so that the ordinary housewife can afford to have several of them, if desired.

Obviously the flange 5 may be of any different outline, if preferred.

90 My invention is not limited to the particular embodiment thereof described and illustrated.

I claim:

1. A carton discharging spout comprising 95 a frame, a spout on one face thereof having a self-closing lid, a carton-cutting flange on the opposite frame face, and a spout locking member hinged to the spout and constructed to engage the inner face of the carton and 100

outer frame face, and a fastening catch therefor.

2. A carton discharging spout comprising a frame, a spout on one face thereof, a carton cutting segmental flange on the opposite frame face, a carton inner wall face engaging member adjacent the frame with its inner end extended through the spout to engage the inner carton wall and a fastening catch therefor on the outer frame face engaging the outer end of the locking member.

3. A carton discharging spout comprising a frame, a spout thereon with a lid, a carton cutting flange on one face of the frame, a swinging carton engaging member pivotally supported by said frame, the inner end of which is adapted to engage the inner wall of the carton and the outer end of which is adapted to engage the outer wall of the frame, and a fastening catch therefor.

4. A carton discharging spout comprising a frame, a spout thereon with a lid, a pointed carton cutting flange on the frame, a locking member pivoted to extend through the frame and engage the carton in locking position on its inner wall face and a fastening catch therefor.

5. A carton discharging device comprising a frame, a lid thereon, a segmental pointed carton cutting flange thereon with a carton receiving slot therein by which to secure the flange and frame to the carton, a locking member positioned to follow the flange into the carton and pivoted to turn across the frame and engage the inner face of the wall of the carton and to fasten itself to the frame.

6. A carton discharging device comprising a frame, a carton cutting flange thereon with a frame locking slot to receive the carton and a frame locking member extended through the frame and across one bar thereof on one face and adjacent the spout on the opposite face along a second bar of the frame to engage the inner wall of the carton to lock the frame thereto.

7. A carton discharging device comprising a frame, a carton cutting flange thereon to provide a discharge opening in the carton wall, a spout on the frame registering with the carton cutting flange, and a locking member constructed to enter the opening with the flange and movable axially to a locking position to lock the frame to the carton.

8. A carton discharging device comprising a frame, a carton cutting member on the frame, a spout on the frame registering with the cutting member, and a locking member carried by the spout and constructed cooperatively to engage one side of the carton and one face of the frame to lock the latter to the former.

9. A carton discharging device comprising a frame 1 with a spout 3 and having a blade-like carton cutting member 5 on one face, with a carton engaging edge to cooperate

with the frame to lock the latter to the carton, a locking member 7 pivoted in the spout 3 and having an offset section 8 within the edge of the cutting member and entering the carton therewith and constructed to engage the carton inner wall and the outer end to engage frame 1 to lock the latter to the former.

In testimony whereof, I have signed my name to this specification.

AUGUST F. SCHMIDT.

CERTIFICATE OF CORRECTION.

Patent No. 1,752,352.

Granted April 1, 1930, to

AUGUST F. SCHMIDT.

It is hereby certified that error appears in the printed specification of the above numbered patent requiring correction as follows: Page 2, line 27, claim 4, for the word "thereof" read "therefor"; and that the said Letters Patent should be read with this correction therein that the same may conform to the record of the case in the Patent Office.

Signed and sealed this 29th day of April, A. D. 1930.

**M. J. Moore,
Acting Commissioner of Patents.**
